UNITED STATES PATENT OFFICE.

TYRANNUS P. BUTTERFIELD, OF NORTH INDIANAPOLIS, INDIANA, ASSIGNOR
TO MANVILLE W. BAKER, OF SAME PLACE.

WASHING-MACHINE.

SPECIFICATION forming part of Letters Patent No. 514,703, dated February 13, 1894.

Application filed November 29, 1893. Serial No. 492,327. (No model.)

To all whom it may concern:

Be it known that I, TYRANNUS P. BUTTERFIELD, a citizen of the United States, residing at North Indianapolis, in the county of Marion 5 and State of Indiana, have invented certain new and useful Improvements in Washing-Machines; and I do hereby declare the following to be a full, clear, and exact description of the invention, such as will enable others skilled 10 in the art to which it appertains to make and use the same.

This invention relates to improvements in machines for washing clothes and has special reference to improvements in machines having a suds box with a corrugated concave bottom and a rocking convex rubber, with corrugated face, the object of the invention being to construct the rubber so it will adjust 15 itself to the varying thickness of the clothes 20 between it and the bottom of the suds box, in order that a closer contact may be had between the entire rubbing face of the rubber and the clothes in order to expedite the washing and also to avoid over-rubbing of the 25 clothes in parts.

I accomplish the objects of this invention by the mechanism illustrated in the accompanying drawings in which—

Figure 1 is a view in perspective of my 30 complete machine. Fig. 2 is a view in side elevation showing the near side partially broken away to show the construction and arrangement of the rubber, the figure shows the rocking rubber in dotted lines as it appears when thrown back to allow the operator to turn the clothes or to remove them or renew the supply. Fig. 3 is a detail in partial transverse section of the suds box showing the rocking rubber as constructed in three 35 sections independently movable, and shows portions of two of the sections broken away to better illustrate the construction. Fig. 4 is a detail in side elevation and sectioned, of one of the pieces of the rocking rubber. Fig. 40 5 is a detail showing the construction of the rub-bars on the bottom of the suds box, and Fig. 6 is a detail showing the construction of the cap for closing the water outlet to the suds box.

Similar letters refer to like parts throughout the several views of the drawings.

A is the suds box and is shown in the drawings as having wooden sides and sheet metal bottom, the metal being used on account of the facility with which it can be bent to conform 55 to the curved shape desired. One end of the machine will be provided with the board A' which will present a considerable surface upon which the hand wash board A² will be located, the said board extending only a portion 60 of the way across the width of the machine so as to leave a space between the wash board and the side of the machine to be used as a soap receptacle. The cross strip a, will form a stop to keep the bar of soap from sliding 65 into the suds box and will have a cut under portion to allow the water to drain into the box. The suds box will be supported on the legs A² in the usual manner.

B are the rub-bars to be located on the bottom of the suds box and are corrugated strips of wood arranged transversely across the machine. These strips are separated by the blocks b, and the blocks and strips will be held together by being strung upon the wires 70 B', which wires pass through suitable holes in the ends of the strips and through the blocks as shown, thereby enabling the bottom rub-bars all to be taken out together, and to be handled as one piece when it is desired to remove them in cleaning the machine.

C is a convex corrugated rubber pivotally secured to the sides of the suds box so as to have a swinging movement by means of which the clothes which are placed between the upper rubber C and the lower rubber B are cleansed. The peculiar construction of this upper rubber C by which it may adjust itself to the varying thickness of the clothes in the machine constitutes the principal feature of 85 my invention and will now be particularly described: The rubbers proper are suspended from a frame consisting of the side pieces C' which are joined together at the top by the cross bar c, which cross bar also serves as a 90 handle by which the operator grasps the frame to swing the rubbers. The lower ends of the side pieces are held together by the cross bar c² which also serves an additional purpose, as will be described farther on, and c' is the axle 95 or pivot upon which the frame swings and consists of a hollow tube, preferably a piece

of gas pipe, which is projected through both sides of the frame and projects a suitable distance on each side of the frame, or side pieces, to engage the sides of the suds box. A notch 5 will be cut in each side of the suds box into which the ends of the tube will be dropped so as to hold the frame at a certain position in the box. The upper rubbers will be secured to the two bars c' and c^2 and the rubbers themselves will be made in independently movable sections, three being shown in the drawings although any other number may be adopted if so desired. As shown in the drawings these sections will be constructed 10 of the side pieces D' , curved on their bottom sides to conform to the curvature of the bottom of the suds box, and will have a series of corrugated strips D^2 secured to the bottoms of the side pieces as shown. Each of the sections of the rubber will be provided with the radial slot D^3 and will be attached to the pivoted frame, previously described, by passing the two lower cross bars c' and c^2 through the slot in the sections as shown in Figs. 3 and 4. 15 The cross pin D^7 above the bar c^2 will keep the sections from dropping off of the bars and the depth of the slot will regulate the height of the adjustment of the sections on the frame. The sections will be weighted sufficiently 20 heavy to give the desired rubbing pressure on the clothes and will cause the rubbers to drop down sufficiently to always be in contact with the clothes, but on the other hand will be free to move up again when the thickness 25 of the goods underneath the rubbers may require it, thus preventing the machine from rubbing to excess on the highest place as would be the case if the top rubber were a continuous and rigid surface as heretofore 30 used.

In practice the several sections of the rubber will preferably be made, either wholly or in part, of metal in order to give the needed weight and pressure and also to prevent the 35 undue swelling of the several sections, which, when made of wood swell up by the action of the steam and water to such an extent as to interfere with the freedom of movement of the sections.

Passing through the tubular pivot C' is an iron rod R , the ends of which are bent back at right angles and extended to a point about midway between the pivotal point of the frame and the end of the machine next the 45 operator, where the extreme ends are then again turned in at right angles and are dropped into the slots a^3 in the sides of the machine thus forming a double hinged con-

nection of the frame with the suds box and thereby enabling the rubbers to be thrown back and raised out of the way for convenience in reaching the clothes in the suds box. The position is shown in the dotted lines in Fig. 2.

M is the outlet through which the suds is withdrawn in changing the water in the machine and will preferably be closed by the pivoted cap N which is secured to the machine by the screw n , so it can be thrown around to expose the opening. A rubber or leather packing secured to the inside of the cap will make the closure water tight.

I claim—

1. In a washing machine a suds box having concave stationary rub-bars on its bottom in combination with a rocking rubber pivotally secured to the sides of the machine and having handle bars by which the rubber may be vibrated, said rocking rubber being made in separately movable sections that will rise and fall automatically as the bulk of clothes beneath such section is increased or diminished substantially as described and for the purposes specified.

2. In a washing machine having a concave rubber on the bottom of the suds box, the combination therewith of a rocking rubber pivotally secured to the sides of the machine and constructed of the following parts: the side pieces C' , top cross piece c , tubular cross bar c' having projecting ends to form pivots by which the rubber will be suspended, and the cross bar c^2 , a rubber proper constructed of several sections each of which sections are provided with a radial slot to receive the cross bars c' and c^2 to control the movement of the sections, and cross pins D^7 all for the purposes substantially as described and specified.

3. In a washing machine having a rocking rubber, the tubular pivot extending from one side of the rubber to the other and forming a tie rod to connect the side pieces of the handle bar frame and projecting at either end to form the pivots for the rubber and a rod projected through the tubular pivot and bent at right angles to form an arm, the extreme ends of which will be removably pivoted to the frame of the machine for the purposes specified.

In testimony whereof I affix my signature in presence of two witnesses.

TYRANNUS P. BUTTERFIELD.
